US0D1046157S

(12) **United States Design Patent** (10) Patent No.: **US D1,046,157 S**
(45) Date of Patent: ** Oct. 8, 2024

(54) SCANNER

(71) Applicant: **CANON MEDICAL SYSTEMS CORPORATION**, Otawara (JP)

(72) Inventor: **Seishiro Takano**, Kanagawa (JP)

(73) Assignee: **Canon Medical Systems Corporation**, Otawara (JP)

(**) Term: **15 Years**

(21) Appl. No.: **29/839,411**

(22) Filed: **May 20, 2022**

(30) Foreign Application Priority Data

Jan. 19, 2022 (JP) ..... 2022-000845 D

(51) LOC (14) Cl. **24-01**

(52) U.S. Cl.

USPC **D24/158**
